UNITED STATES PATENT OFFICE.

WILLIAM O. YANCEY, OF BLUE ISLAND, ILLINOIS.

IRON FOR BAKING PASTRY CONTAINERS.

Application filed April 17, 1925. Serial No. 23,806.

This invention relates to improvements in irons for baking pastry, and more particularly for baking thin pastry shells especially for sandwiches of various kinds, such as ice cream, salad and the like, and in a form suitable for vending in public places.

The object of the invention is to provide a new and novel form of iron, similar in its general form and manner of use, to a waffle iron, but differing essentially in the design and form of the baking molds.

A preferred form of the iron is disclosed in the accompanying drawings, in which—

Figure 1 is a perspective view of the iron in closed position.

Figure 2 is a top plan view of the iron in open position.

Figure 3 is a cross-sectional view through the iron, and

Figure 4 is a perspective view of the pastry form made in the iron.

The iron consists generally of two irons or mold members 1 and 2, of cast iron or like material, and rectangular in shape.

The irons are hinged together at one end by a suitable hinged connection or joint 3, and at their opposite ends, each is provided with a handle 4 preferably of the non-conductive or insulated type consisting of coils of wire surrounding the solid portion of the handle.

Referring to the irons in the position shown in Figure 1, the lower iron 2 consists of two depressed or recessed molds 5, 5 of the same size, shape and configuration, arranged side by side but separated by a relatively wide dividing wall 6 slightly lower than the marginal walls of the molds. The surfaces of the molds are ornamented with grid-like designs, cast in relief and primarily for the purpose of impressing a distinctive and attractive design on the surface of the shells to be baked therein.

The upper iron 1 consists of two cores 7, 7 identical in size and shape, each being square and provided with beveled edges. These cores are countersunk in the upper iron so that they appear in relief in the inner surface thereof, and when the two irons are brought together, the cores of the upper iron register with the complementary depressed molds of the lower iron with sufficient clearance between to form a pair of similar mold cavities equal to the thickness of the shell or pastry form to be baked, as clearly appears in Figure 3.

Extending around as well as between the cores 7, 7 are flat surfaces 8, their marginal portions engaging the edges of the recessed molds to seal the iron when the same is in closed position. From the surface between the cores, however, projects a rib 9 with beveled sides meeting at an obtuse angle. This rib is relatively shallow, and as shown in Figure 3 its beveled edge is adapted to come into close proximity to the top face of the dividing wall 6 of the lower iron 2 when the parts are closed.

To operate the iron, the required amount of batter is placed in each of the molds in the bottom half of the iron after the same has been heated to the proper temperature for baking. By closing down the top half the batter is spread, filling the cavities between the two parts of the iron, thereby forming two shells or forms of pastry. Moreover, due to the conformation of the irons, the batter spreads from one mold cavity to the other and forms a thin connecting layer between the adjacent edges, which is partially severed or creased lengthwise by the beveled edge of the rib 9.

When baked, the two connected forms are removed from the iron and while still hot, the sandwich filling is put into one half and the other folded over upon it, along the fold line provided for this purpose in the connecting layer, which ordinarily remains intact so that the sandwich retains a more substantial form while being consumed.

As already suggested, an iron of this type is especially desirable for the dispensing of ice-cream or other food products from counters, booths and confection stands, and has a distinct advantage over the usual method of dispensing in that it completely encloses the product in an edible shell which will remain intact during the consumption of the whole.

I claim as my invention:

1. A pastry baking iron for the purpose described, comprising hinged-together sections having pairs of complementary molds and cores adapted to form similarly shaped mold cavities when said sections are closed, said pairs of molds and cores being separated by dividing walls spaced relatively close together, whereby the shells baked in said cavities are joined together at adjacent edges by a thin connecting layer of the pastry.

2. A pastry baking iron comprising two

hinged-together sections, one being provided with a pair of rectangular recessed molds and the other with a pair of complementary cores and adapted to form therebetween a pair of rectangular and relatively shallow mold cavities, said pairs of molds and cores being separated by complementary dividing walls adapted to form a narrow space connecting the adjacent sides of said mold cavities, one of said walls being in the form of a rib having beveled edges.

Signed at Chicago, Ill., this 4th day of April, 1925.

WILLIAM O. YANCEY.
